(57) **CLAIM**

The ornamental design for a case for electronic device, as shown and described.

DESCRIPTION

FIG. 1 is a front perspective view of a case for electronic device, showing our new design;
FIG. 2 is a front view thereof;
FIG. 3 is a rear view thereof;
FIG. 4 is a left-side view thereof;
FIG. 5 is a right-side view thereof;
FIG. 6 is a top view thereof;
FIG. 7 is a bottom view thereof;
FIG. 8 is a bottom perspective view thereof shown in an alternate position in an environment of use;
FIG. 9 is another left-side view thereof shown in the alternate position in an environment of use;
FIG. 10 is an enlarged view of the encircled portion 10 in FIG. 4; and,
FIG. 11 is an enlarged view of the encircled portion 11 in FIG. 4.

The even-dash broken lines illustrating portions of the case for electronic device form no part of the claimed design. The even-dash broken lines illustrating an electronic device in FIGS. 8 and 9 form no part of the claimed design. The dot-dash broken lines encircling enlargement portions of the claimed design form no part of the claimed design.
